UNITED STATES PATENT OFFICE.

JULES GERSANT, OF LARKHALL RISE, AND ARCHIBALD GEORGE BUTTIFANT,
OF LEE, ENGLAND.

MACHINE FOR FUSING TOP AND BOTTOM SEAMS OF METAL CANS OR LIKE RECEPTACLES.

SPECIFICATION forming part of Letters Patent No. 671,547, dated April 9, 1901.

Application filed October 22, 1900. Serial No. 33,933. (No model.)

To all whom it may concern:

Be it known that we, JULES GERSANT, a citizen of the French Republic, residing at 1 Netherford road, Larkhall Rise, in the county 5 of Surrey, and ARCHIBALD GEORGE BUTTIFANT, a subject of the Queen of Great Britain and Ireland, residing at 32 Southbrook road, Lee, in the county of Kent, England, have invented new and useful Improvements in 10 Machines for Fusing the Top and Bottom Seams of Metal Cans or Like Receptacles, of which the following is a specification.

Our invention relates to improvements in 15 machines for fusing the top and bottom seams of metal cans and like receptacles by the process of fusing together within the seams the contacting parts of the coating with which is covered the metal from which the cans and receptacles are made, the machines being designed more especially for use in the manufacture of cans and the like made from tinned 20 sheet iron.

We attain our object by the mechanism 25 illustrated in the accompanying drawings, in which—

Figure 1 is a part sectional side view of half of the machine, and Fig. 2 a similar view of the other half. Fig. 3 is a sectional front view of a detail, and Fig. 4 a plan of the 30 driving arrangement.

Supported on a suitable base-plate *a* we provide standards *b*, carrying a table *c*, above which is the rotatable platform *d*, attached to the vertical shaft *e*, the lower end of which 35 is free to run in the footstep *f*. Below the table *c* is an air-chamber *g*, communicating with a fan. The chamber *g* has a lower stuffing-box *h*, through which passes the shaft *e*, a pipe *i* being attached to the under side of 40 the table *c*, so as to run in the second stuffing-box *j*. Above the platform *d* is a gas-chamber *k*, outside which is an air-gallery *l*, communicating with the pipe *i*, and consequently with the air-chamber *g*. Gas is supplied to 45 the gas-chamber *k* through holes *m* in the supply-pipe *n*. The pipe *n* has a plug *o* at its lower end, which plug rests in the recess *p* at the upper end of the shaft *e*. Intermittent rotation can be given to the platform *d* 50 by a ratchet-wheel *q*, attached to the shaft *e* and operated by a pawl *r*, carried at the outer end of the arm *s*, coupled at *t* to the connecting-rod *u*, worked by the crank *s*, carried by the shaft *w*, which is rotated by the spur-wheel *x*, which is revolved by the pinion *y* on a lower shaft *z*, the lower shaft having the fast driving-pulley *A* and the loose pulley *B*.

Equidistant around the platform *d* are the tubular sockets *C*, within which are free to ride up and down the plungers *D*, having the rollers *E* free to travel around the upper surface of the platform *d*. The plungers *D* are tubular at their upper ends and receive the stems *F*, each stem carrying at its upper end 60 a small table *G*, on which to stand a can *H*, which is to have its top or bottom seamed. The table *G* has a surrounding rim *J* and a false bottom *K*, movable within the rim *J*, and having two pins *L* attached to its lower 65 surface and passing freely through holes in the table *G*. Between the lower end of each stem *F* and the bottom of the tubular part of its respective plunger *D* is a spiral spring *M*. The plungers *D* are kept from rotating in the sockets *C* by a screw *N* entering a slot *O* in the plunger. Behind each socket *C* is a standard *P*, having the bolt *Q* for adjustment in a slot in the platform *d*. Concentrically over each socket *C* is a circular burner *R*, which can be raised and lowered by the screw *S* and guided by the bolt *T* sliding in the slotted opening *U* provided in the standard *P*. The burner *R* has a ring-gallery *V*, receiving gas and air from the pipe 80 *W*, communicating with the mixing-bulb *X*, which receives air from the gallery *l* by the pipe *b'* and gas from the chamber *k* through the pipe *a'*, regulating-taps being provided on the pipes *a'* and *b'*. The air and gas passes 85 outward from the gallery *V* through the holes *d'* into the circumferentially-slotted gallery *e'*, provided with the flame-slot *f'*. There is an overhanging ledge *g'* above the slot *f'*, which comes on the top of the can *H* being 90 operated on. At the edge of the table *c* is a gap *g''*, having inclines *h'*, which slope downward one another. The first part of the bottom of the gap *g''* is depressed, as at *i'*, to a greater extent than the rest of it. The ob- 95 100

- ject of the gap g' is to allow the plungers D to descend as the cans H come around on completion of each rotation of the platform d. The depression i' allows the plungers D 5 to descend sufficiently to cause the pins L, by contact with the platform d, to push up the false bottom K and bring the bottom of the can H above the rim J, and so into position to be struck off for its place to be taken by 10 another can. The cans H, after passing in succession under each of the burners R, are struck off the tables G by the following means: Held above and below in a suitable standard j' is a spindle k', having a projecting arm l' 15 at or near its upper end and another arm m' at or near its lower end. The spindle k' is encircled by the spiral spring n', the ends of which are held in such manner that the arms l' and m' incline toward the direction in which 20 the cans H approach them. When in the onward course of the platform d the lower arm m' is pushed forward by one of the sockets C, the upper arm l' will also be moved forward, and as soon as the socket C has 25 passed sufficiently to release the lower arm m' it and the upper one l' will be caused by the spring n' to fly back in the opposite direction to that of the platform d, whereupon the upper arm l' will strike off the can H. 30 As the platform d advances the plunger D is pushed by the higher part of the bottom of the gap g' , so that the false bottom K falls and again exposes the rim J ready for the reception of the next can. 35 If desired, the platform d may be revolved continuously by any suitable means instead of intermittently by means of the ratchet wheel q and pawl r.
- The operation of the machine is as follows: 40 The platform d is intermittently rotated by the means already mentioned, and each can H having its double-seamed top or bottom seam formed has that seam played on by the flame of the burner R, whereby the contacting coatings of the metal are fused together, 45 the fusion being complete on the platform d completing its revolution. Each can as it comes to the gap g' is struck off, as above explained, and its place taken by another can, 50 and so on.

What we claim as our invention, and desire to secure by Letters Patent, is—

In machines for fusing the top and bottom seams of metal cans and like receptacles, a table: standards supporting the said table: a revoluble platform above the said table: a vertical shaft carrying the said platform: means for intermittently or continuously moving the said shaft and platform: an air-chamber below the said platform: an air-gallery above the said platform: means for supplying air to the said chamber and gallery: a gas-chamber above the said platform: means for conveying gas to the said gas-chamber: tubular sockets equidistantly arrayed around the revoluble platform and hanging below it: plungers slidable in the said tubular sockets and having tubular upper ends: rimmed tables having stems to fit into the said tubular ends of the said plungers: springs between the bottoms of the tubular ends of the plungers and the bottom ends of the said stems: false bottoms to the rimmed tables: means for raising the said bottoms to the level of the rims of the tables: radially-adjustable standards behind each tubular socket: horizontal ring burners attached in an adjustable manner to the said standards: means for moving the said burners in a vertical direction: pipes conveying mixed air and gas to the said burners: mixing-bulbs with which the said pipes communicate: air and gas pipes entering the said bulbs and communicating respectively with the air-gallery and gas-chamber: means for regulating the supply of air and gas to the bulbs: a gap in the revoluble platform: sloping ends to the said gap: a rail bottom to the said gap and connecting the sloping ends of the said gap: means for striking off each can after it has made a complete revolution with the revoluble platform, substantially as described and illustrated.

In testimony whereof we have signed our names to this specification in the presence of two subscribing witnesses.

JULES GERSANT.

ARCHIBALD GEORGE BUTTIFANT.
